UNITED STATES PATENT OFFICE.

ROBERT EDWARD WHITE, OF SMITHS CREEK, MICHIGAN.

TRACTOR.

Application filed April 17, 1922. Serial No. 553,584.

To all whom it may concern:

Be it known that I, ROBERT EDWARD WHITE, a citizen of the United States of America, residing at Smiths Creek, in the county of St. Clair and State of Michigan, have invented certain new and useful Improvements in Tractors, of which the following is a specification, reference being had therein to the accompanying drawings.

This invention relates to tractors and the invention consists in the structural features and arrangement of parts hereinafter described and fully illustrated in the accompanying drawings wherein:—

Figure 1 is a plan view of the improved tractor;

Figure 2 is a longitudinal sectional elevation of the same, taken on line 2—2 of Figure 1;

Figure 3 is a diagrammatic side elevation showing how the wheels adapt themselves to uneven ground;

Figure 4 is a rear view of the tractor;

Figure 5 is a fragmentary front view showing a pair of brackets respectively carried by two members of the frame to guide them on a relative pivotal movement;

Figure 6 is a sectional view of a braking control for steering, the section being taken on line 6—6 of Figure 1.

In these views the reference characters 1 and 2 designate complementary frame members which are co-extensive from front to back, the former having a width preferably somewhat greater than the latter. 3 is a housing for a differential gearing, and 4 tubular extensions of said housing, in which are mounted aligned shafts 5 adapted to be differentially driven through said gearing.

6 is the usual engine through which the shafts 5 are driven, said engine being mounted preferably on the larger frame member. 7 and 8 designate respectively front and rear pairs of carrying wheels, and

9 a pair of intermediate and somewhat larger wheels. 10, 11 and 12 are the axle members for the front intermediate and rear wheels respectively. Each of said axle members is formed in two parts, which are independently journaled upon the respective members 1 and 2 in suitable bearings 13, said parts being aligned when said frame members are in registering relation.

The frame members 1 and 2 pivotally engage the tubular members 4, and are adapted to swing independently about the axis es-

tablished by said members. Said frame members are guided in such relative movement by engagement of an arm 14, forwardly projecting from the member 2, in a slot 15 vertically formed in a bracket member 15^a secured to the front end of the member 1. This engagement, while permitting a free relative angular movement between the frame members, maintains the latter in proper proximity, and decreases the strain on the members 4. Each front axle member 10 is driven from the corresponding shaft 5 through a train of gears 16, 17, 18, 19 and 20 and the intermediate axle sections 11 are driven from the front axle through gear trains 21, 22, 23. The rear axle members 12 are each driven through gear trains 16, 24, 25. Thus it is seen that the invention provides a six-wheel drive, insuring a very powerful traction.

Upon the outer end portions of the shafts 5 brake drums 26 are respectively mounted and are engaged by brake-bands 27. Provision is made for alternatively exercising a braking effect through the bands 27 and drums 26 upon either drive shaft 5, so as to concentrate the power upon the other shaft and thereby effect the desired turning of the vehicle. Thus, 28 is a slide bar mounted transversely of the vehicle and having wedge forming end portions engaging the brake bands 27 to selectively tighten the same upon their brake drums, according to the direction of sliding of said bar, and 29 is a control lever for said bar intermediate fulcrumed above the latter, as indicated at 29^a, and pivoted at its lower end to said bar. The ends of the bar engage between rolls 30 secured to the brake band extremities (see Figure 6) and are thus adapted to control the tension of said bands.

A winch 31 may be mounted on the shaft 32 of one of the gears 22 to adapt the tractor to pull itself out of mud holes or the like.

It is a distinctive feature of the described tractor that four supporting wheels thereof will engage the ground, however uneven the surface of the latter may be. Thus the described tractor is peculiarly adapted for use upon rough or hilly grounds, since it maintains a firm support under all conditions of use, and furthermore develops under all conditions a powerful traction, since all of the wheels are driven.

What I claim as my invention is:—

1. A tractor comprising a pair of longi-

- tudinal frame members, a transverse tubular member pivotally connecting said frame members, three or more pairs of ground engaging wheels journaled on said frame members, a motor mounted upon one frame member, transmission mechanism extending through said tubular member, and gearing upon each of said frame members connected to said transmission mechanism for driving 10 all of said wheels, the pivotal connection of said frame members allowing at least four of said driven wheels to engage the ground.
2. A tractor frame comprising relatively pivotal members having a common axis, a plurality of carrying wheels of varying diameters independently mounted upon each of said members, driven pinions parallelly arranged with respect to said wheels, and aligned gear connections between said pinions and wheels respectively for driving the latter.
3. A tractor comprising a pair of complementary frame members arranged side by side, means pivotally connecting said members intermediate their length, a plurality of carrying wheels of varying diameters independently mounted upon each of said members, driven pinions and gears carried by said frame members and wheels respectively for transmitting the driving torque to each wheel separately.
4. A tractor comprising a frame composed of relatively pivotal complementary mem-
- bers, carrying wheels of varying diameters independently mounted upon each of said complementary members, intermeshing gears carried by said wheels and frame members respectively, and means for driving said gears to drive each of said wheels separately.
5. A tractor comprising a frame formed of complementary relatively pivotal members, front, rear and intermediate wheels independently mounted upon each of said frame members respectively, said intermediate wheels being of greater diameter than 45 said other wheels, and means for driving each of said wheels.
6. In a tractor the combination of a pair of rigid longitudinal frame members, three or more ground engaging wheels on each of said rigid frame members, and means for pivotally connecting said rigid frame members to allow at least four of said wheels to engage the ground under all conditions.
7. In a tractor, the combination of a pair of rigid longitudinal frame members, three or more ground engaging wheels on each of said frame members, means for positively driving all of said wheels, and means for pivotally connecting said rigid frame members to allow at least four of said driven wheels to engage the ground under all conditions.

In testimony whereof I affix my signature.

ROBERT EDWARD WHITE.
